PISTON RING SPLITTING AND TRIMMING MACHINE

Albert H. Bates, Rockford, Ill., assignor to Burd
Piston Ring Company, Rockford, Ill., a corpora-
tion of Illinois

Application January 1, 1945, Serial No. 570,999

6 Claims. (Cl. 29—33)

1

This invention relates to an improved machine for cutting the gaps in piston rings and thereafter trimming the gaps to a predetermined width in relation to outside diameter.

The principal object of my invention is to provide in a single compact machine facilities for lining up in a series of rings the notches that are cast in the inner peripheries at the gap points and other facilities for supporting a stack of rings thus aligned and moving the same at a feed rate toward the gap cutters and gap miller, which are arranged on opposite sides of a sizing ring through which the rings, after the gaps are cut therein, are caused to move for compression down to a predetermined outside diameter, preparatory to the milling operation. This combining of operations in such a practical and efficient manner obviously means a considerable saving in time and labor and a corresponding reduction in the cost of production of piston rings, besides insuring closer uniformity in the product.

Another object is to provide a machine of the kind mentioned, in which the same rod that is used for lining up the notches in the rings is adapted to be used in transferring the stack of aligned rings onto the V-bed of the machine, means being provided in the machine for support of said rod at its opposite ends to insure keeping the notches aligned up to the time the gap is cut, the rings sliding on the rod as a guide until they reach the gap cutters, and other provision being made for thereafter guiding the rings by their gaps up to the point where the rings have their gaps milled to size in relation to their outside diameter.

The invention is illustrated in the accompanying drawings, in which—

Fig. 1 is a view partly in side elevation and partly in longitudinal section of a machine made in accordance with my invention;

Fig. 2 is a cross section on the line 2—2 of Fig. 1, and

Figs. 3 and 4 show the closed ring blank and the same ring after the splitting and trimming operation, respectively.

The same reference numerals are applied to corresponding parts throughout the views.

Piston rings for automotive engines are cast out of round; the ring is then side ground to produce true, flat, smooth and parallel surfaces on both sides. An elliptical ring blank of this kind is illustrated at 10 in Fig. 3 and has a notch 11 cast in its inner periphery in that portion 12 between the parallel dotted lines 13 and 14, which is ultimately cut out to form a gap and leave the ring

2

in the form of an open, resilient spring like that illustrated at 15 in Fig. 4. The gap 16 in the ring 15 is wide enough so that the ring is compressible to circular form. The gap indicated at 16 is a trifle wider than the gap 13—14 produced by cutting out the slug 12 from the blank 10, because, as will soon appear, the ring 15, after the so-called splitting operation, is milled in the gap in a so-called trimming operation to make the gap a predetermined width in relation to the outside diameter of the ring. The rings, after the split and trim operations, are machined on their outer and inner peripheries and may, if necessary, be given a finish trim operation in the gap. However, the machine of the present invention is concerned only with the splitting and trimming operations.

The machine comprises a base 17, on one end of which is mounted a hydraulic cylinder 18 containing the ram 19 used for moving a stack of rings like those indicated in dotted lines at 20 at a feed rate toward the other end of the base toward the gap cutters 21, sizing ring 22 and gap miller 23. The sizing ring 22 is formed as part 25 of a standard 24 that is suitably detachably secured onto the end portion of the base. A horizontal V-bed 25 extends longitudinally of the base between the cylinder 18 and standard 24, and the ram 19 is movable lengthwise thereof 30 between the laterally and vertically adjustable side pieces 26 forming said V-bed. The side pieces 26 are adjusted to support the stack 20 in coaxial relationship to the sizing ring 22 so that the rings will enter the large inner end of the tapered portion 27 of the bore of said ring as the stack is moved by the ram toward the ring along said bed. The rings in the stack 20 are closed blanks like that shown in Fig. 3 from the face plate 28 on the ram 19 up to the gap cutters 21, but the cutters 21 cut out of the lugs 12, and hence those rings from the cutters 21 forwardly are all split rings similar to that shown in Fig. 4 and are therefore compressible radially to substantially circular form. These split rings, in moving forwardly through the tapered portion 27 of the bore of the sizing ring 22 at a feed rate in the movement of the stack 20, are gradually compressed radially, as illustrated in dotted lines at 29 in Fig. 1, until they reach the short end portion 30 50 of the bore of the sizing ring that is of a uniform, predetermined diameter. The diameter of the end portion 30 of the bore is only a few thousandths of an inch larger than the predetermined outside diameter of the rings in relation to which the gaps 16 are to be milled to a predetermined

width, and the gap milling cutter 23 is of a thickness that will insure milling of the gaps 16 to said predetermined width.

A cylindrical rod 31 that is substantially horizontally disposed, parallel to and above the longitudinal center line of the V-bed 25, has one end fitting slidably in a hole 32 provided therefor in the face plate 28 on the ram 19, and has its other end supported in a longitudinally extending groove 33 provided in a bracket 34 suitably secured at 35 to the inner side of the sizing ring 22. The rod 31 fits in the aligned notches 11 in the cast ring blanks 10, forming the large rear portion of the stack 20, and acts as a guide for the ring blanks in the movement of the stack toward the cutters 21 to keep the notches 11 in alignment and insure the cutting out of the slugs 12 from the proper portion of the ring blanks, the blanks being of elliptical form, as disclosed in Fig. 3, and requiring the cutting out of the slugs from the flat side where the notches 11 are provided, to permit subsequently closing the rings by compression to substantially circular form. The bracket 34 has an arcuate portion 36 reaching under the cutters 21 in the manner shown in Fig. 1, and there is a shoulder 37 on the end of this arcuate portion at the inner end of the groove 33 to serve as an abutment for the end of the rod 31, so that the rod will remain stationary as the ram 19 moves forwardly to move the stack 20 at a feed rate toward the cutters 21, the ram in such movement telescoping on the rod. When the ram has moved to the point where it strikes a lever 38 that is suitably connected with a hydraulic control valve, the ram stops automatically as a result of the automatic operation of the valve, whereupon the operator can, by manual operation of the lever 38, cause the ram to be returned under hydraulic pressure to the starting position, and the machine is ready to receive another batch of ring blanks 10 in a stack 20 to continue the splitting and trimming operation described.

While the ram 19 is moving a stack 20 at a feed rate toward the cutters 21, the operator makes ready the next stack of ring blanks, as indicated at 20' in Fig. 1, placing a group of these blanks over a bracket 39 that projects from a housing 40 that is preferably on the same end of the base 17 with the cylinder 18. A rod 31', like the rod 31, rests in a groove 41 in the bracket 39 and has a detachable driving connection at its inner end with a spindle 42 that projects from the housing 40 and has suitable drive means connected therewith in said housing to turn the same fairly slowly but continuously. In that way, the ring blanks are supported on the rod 31' and turned individually until the rod 31' rides into the notches 11, after which the rod turns with respect to the ring blanks. Usually all of the rings in a group will have their notches brought into alignment in this way, but should one or more rings in a group fail to be turned to the point of bringing their notches into alignment with the others, the operator will immediately detect that because of the small notches 43 that are provided on the outer peripheries adjacent the notches 11 (see Fig. 3), and of course these few rings can be turned quickly to the necessary extent to make the stack ready for transfer into the machine onto the V-bed 25, the rod 31 or 31', as the case may be, being detached from the spindle 42 and taken hold of at both ends to act as a carrier for the stack of rings in the transfer. The other rod previously used as a guide for the

stack of rings is then connected with the spindle 42 and used to make ready the next stack.

A pair of V-shaped wire springs 44 are mounted on brackets 45 fastened to the back of the sizing ring 22, and are disposed in parallel spaced relation on opposite sides of the bracket 34 and are normally flexed upwardly, as indicated in dotted lines in Fig. 1, by contact on the relatively smooth cylindrical exterior of the stack 20 during the feeding of ring blanks to the cutters 21. However, when the ram 19 reaches the forward end of its stroke and is then backed away, these springs have an opportunity to spring downwardly behind the last ring blank, as indicated in full lines in Fig. 1, so as to hold the stack intact and avoid the likelihood of the last one or two, or even three, ring blanks falling out of place and requiring separate handling by the operator. Both sides of the V on each of these springs 44 are at approximately 45° with respect to a vertical, so that these springs will ride into and out of operative position easily; that is to say, when the ram 19 backs away, these springs ride over the back of the endmost ring blank in the stack, and serve by their light pressure on said blank to prevent toppling over of the last few blanks away from the stack. But when the new stack of rings is moved into position behind the other blanks, the springs 44 yield readily and are moved out of the way by pinching contact between the ring blanks as the stacks are moved together.

After the slugs 12 are cut from the ring blanks 10 by the cutters 21, the split rings are guided by their gaps, first by contact at 46 with the attaching end portion of the bracket 34, and then by contact with a guide blade 47 that extends longitudinally of the tapered portion 27 of the bore of the sizing ring 22. The rings cannot, therefore, turn out of position in their movement at the feed rate from the cutters 21 to the milling cutter 23, and of course as soon as the milling cutter 23 starts cutting in the gap of a ring as it passes through the end portion 30 of the bore in the sizing ring, there is no longer any need for any guiding action, as the cut itself forms a guide. The milling cutter 23 projects into the upper end portion 30 of the bore of the sizing ring immediately behind the guide blade 47, as clearly shown in Fig. 1, and there is an arcuate notch 48 cut in the sizing ring above the end portion 30 of the bore for clearance of the cutter. A discharge guide chute 49 of I-beam cross-section projects into the end portion 30 of the bore of the sizing ring below the milling cutter 23, and as the freshly milled rings emerge from the bore they drop onto the chute 49 and are guided between the flanges 50 thereof, the web portion 51 entering the gaps.

A shaft 52 is shown connected to the cutters 21 and, it is understood, is suitably connected to the driving means. The same is true regarding the shaft 53, shown connected to the milling cutter 23. A bracket 54 is shown projecting from the sizing ring 22 over the cutters 21 and carries a downwardly projecting blade 55 which reaches between the cutters 21 and serves as a deflector for the slugs 12 cut from the ring blanks, to avoid likelihood of these slugs being thrown upwardly and outwardly from the machine in the speedy rotation of the cutters, which might cause injury to the operator or a passerby.

The operation of the machine is believed to be clear from the foregoing description. The splitting and trimming of rings is done quickly and accurately and in such a practical and efficient

manner that the cost of production of piston rings is greatly reduced.

The appended claims have been drawn with a view to covering all legitimate modifications and adaptations.

I claim:

1. In the manufacture of split piston rings, or the like, a support slidably supporting as a tube a plurality of closed piston ring blanks in stacked relation face to face, whereby each blank is held properly positioned normal to an axis of operation by tight contact of its opposed faces with neighboring blanks in the stack, means for moving the stack axially at a feed rate relative to said support, cutter means intermediate the ends of said support for cutting gaps in said closed blanks in the movement of the stack, said cutter means comprising a pair of spaced substantially parallel rotary cutters, and a deflector between said cutters and arranged to be struck by the slugs cut from the ring blanks and carried with the cutters in the turning thereof to stop said slugs and deflect the same in a predetermined direction away from the cutters.

2. In the manufacture of split piston rings, or the like, a support slidably supporting as a tube a plurality of closed piston ring blanks in stacked relation face to face, whereby each blank is held properly positioned normal to an axis of operation by tight contact of its opposed faces with neighboring blanks in the stack, means for moving the stack axially at a feed rate relative to said support, cutter means intermediate the ends of said support for cutting gaps in said closed blanks in the movement of the stack, said support being substantially horizontally disposed and the stack of ring blanks being movable over the same, and means above said support yieldably engaging the ring blanks from above to prevent toppling of the rearmost blanks when the feed means is retracted relative thereto as when additional ring blanks to be fed by the feed means are to be placed in the machine.

3. In the manufacture of split piston rings, or the like, a support slidably supporting as a tube a plurality of closed piston ring blanks in stacked relation face to face, whereby each blank is held properly positioned normal to an axis of operation by tight contact of its opposed faces with neighboring blanks in the stack, the closed ring blanks each having a locating notch provided therein on its inner periphery, guide means in spaced relation to one end portion of the support entered in the locating notches to maintain alignment thereof in the movement of the stack, means for moving the stack axially at a feed rate relative to said support, cutter means intermediate the ends of said support in alignment with the aforesaid guide means for cutting gaps in said closed blanks at the notched portions in the movement of the stack, said cutter means comprising a pair of spaced substantially parallel rotary cutters, and a deflector between said cutters and arranged to be struck by the slugs cut from the ring blanks and carried with the cutters in the turning thereof to stop said slugs and deflect the same in a predetermined direction away from the cutters.

4. In the manufacture of split piston rings, or the like, a substantially horizontal support slidably supporting as a tube a plurality of closed piston ring blanks and a plurality of split piston ring blanks in stacked relation face to face, whereby each blank is held properly positioned normal to an axis of operation by tight contact

of its opposed faces with neighboring blanks in the stack, the closed ring blanks each having a locating notch provided therein on its inner periphery, an elongated rod entered in the locating notches to maintain the same in alignment in the movement of the stack, means for demountably supporting one end of said rod in parallel relation to and above one end portion of said support, a guide for split piston rings over the other end of said support demountably supporting the other end of said rod thereon, means for moving the stack axially at a feed rate relative to said first support, and cutter means intermediate the ends of said support and disposed adjacent the last mentioned end of said rod for cutting gaps in said closed blanks at the notched portions in the axial movement of the stack.

5. In the manufacture of split piston rings or the like, a support slidably supporting as a tube a plurality of closed piston ring blanks in stacked relation face to face, whereby all of said blanks are held positioned normal to an axis of operation by tight contact of their opposed faces with neighboring blanks in the stack, means for moving the stack axially at a feed rate relative to said support, cutter means intermediate the ends of said support for cutting gaps in the closed blanks in the forward feed movement of the stack, guide means extending lengthwise relative to said support in close posterior relation to said cutter means and aligned therewith so as to enter the ring gaps made by said cutter means and prevent rotation of the rings and maintain the gaps in alignment during the further forward feed movement of the stack, a sizing ring at the outer end of said support having an inwardly flared entrance end arranged to receive split rings in the forward feed movement of the stack, the split rings being compressed radially in said sizing ring in the forward feed movement, whereby the gaps cut by the aforesaid cutter means are substantially reduced in width, and a cutter at the outlet end of said sizing ring in alignment with and closely adjacent the outer end of said guide means so as to be operable in the gaps and of a thickness slightly greater than the width of the reduced ring gap to mill the gaps in the rings all to a predetermined width before the rings are discharged from the sizing ring.

6. In the manufacture of split piston rings, or the like, a support slidably supporting as a tube a plurality of closed piston ring blanks in stacked relation face to face, whereby all of said blanks are held positioned normal to an axis of operation by tight contact of their opposed faces with neighboring blanks in the stack, the closed ring blanks each having a locating notch provided therein on its inner periphery, means for moving the stack axially at a feed rate relative to said support, cutter means intermediate the ends of said support for cutting gaps in said closed blanks at the notched portions in the forward feed movement of the stack, guide means extending lengthwise relative to said support including one portion in close anterior relation to and aligned with the cutter means slidably received in the locating notches in the closed ring blanks, so as to prevent rotation of said blanks and maintain the notches in alignment with said cutter means during the forward feed movement of the stack relative to said support, said guide means including another portion in close posterior relation to and aligned with the cutter

means so as to enter the ring gaps made by said cutter means and prevent rotation of the rings and maintain the gaps in alignment during the further forward feed movement of the stack, a sizing ring at the outer end of said support having an inwardly flared entrance end arranged to receive split rings in the forward feed movement of the stack, the split rings being compressed radially in said sizing ring in the forward feed movement, whereby the gaps cut by 10 the aforesaid cutter means are substantially reduced in width, and a cutter at the outlet end of said sizing ring in alignment with and closely adjacent the outer end of said guide means so as to be operable in the gaps and of a thickness 15 slightly greater than the width of the reduced ring gap to mill the gaps in the rings all to a predetermined width before the rings are discharged from the sizing ring.

ALBERT H. BATES.
